UNITED STATES PATENT OFFICE.

JOHN LEA, OF LONDON, COUNTY OF MIDDLESEX, ENGLAND.

ELECTRIC-ARC LAMP.

SPECIFICATION forming part of Letters Patent No. 281,891, dated July 24, 1883.

Application filed May 25, 1882. (No model.)

To all whom it may concern:

Be it known that I, JOHN LEA, a subject of Her Majesty the Queen of Great Britain, residing at London, in the county of Middlesex, England, have invented certain new and useful Improvements in Electric-Arc Lamps, of which the following is a specification.

My invention has for its object the better regulation of the feed of the carbon or carbons, in order to insure a steady light, and at the same time to employ carbons of great length, so that what is known as a "single lamp"—that is, one pair of carbons acted upon by one set of feeding apparatus—shall burn for a long time without attention. I attain these objects by the mechanism illustrated in the accompanying drawings, in which—

Figure 1 is a front elevation, and Fig. 2 a side elevation, of my improved electric-arc lamp. Fig. 3 is a plan view of the lamp with some of the parts removed to show the circuit-connections more clearly; and Fig. 4 is a diagram of the circuit-connections, the path of the current through the electrodes and solenoid W being indicated by arrows in full lines, and through the magnet M by arrows in dotted lines when the resistance at the arc is normal.

According to my invention, the upper carbon is held in position by rollers a a' a'' , (by preference three,) two of which, a and a' , are mounted in a metal frame, A, which frame also carries a frame, b, in which is mounted the third roller, a'' . This third roller is a riding or jockey roller, adjustable to any given pressure by means of the springs c , adjusting-screw c' , and thumb-nut c'' , the spring being attached to the frame of the jockey-roller at c'' . This jockey-roller, as shown in the drawings, is in the position it would occupy if a carbon of large diameter, (as represented by the dotted lines)—say three-fourths of an inch—be placed in the lamp between the riding or jockey roller a'' on the one side and the two rollers a a' on the other side. Should a carbon of smaller diameter be placed in the lamp, the jockey-roller would close upon it by the action of the spring c , and by means of the nut c'' sufficient tension can be put upon it to prevent its weight revolving the three rollers and allowing the carbon to fall through by gravitation. The roller a is of larger diameter than

the other two rollers, and all these rollers are grooved to allow of different-sized carbons being placed between them. The lower or negative carbon is held in its place by a clamp, n , Fig. 2, and is maintained therein by a screw, n' , so placed as to hold any sized carbons in a line with each other.

The feeding action for lowering the upper carbon as it is consumed is as follows: A solenoid, M, or an electro-magnet is employed, and actuates a gripping-lever, d , for the purpose of revolving the rollers, and this solenoid or electro-magnet is connected as a shunt from the main circuit. This shunt-circuit is divided, to allow of a variable resistance, by being wound differentially or in two parts. When the first part of the wire is wound on, a wire, m , is attached and is brought out of the coil, and then attached to a metal block, e , to which is fastened a spring, f . The second part of the wire, m' , is then wound on, but in the opposite section, and its end brought out and attached to the metal base-plate at i ; or this second wire may be placed in the lamp as a resistance-coil, and a branch wire from the connection run up to the spring, attached to it at one end, and the other end of this resistance-coil attached to the base-plate.

M' is the core of the feeding-solenoid. The metal block e , to which is fastened the spring f , is placed upon an adjusting-screw, g , passing through a block of insulating material, h , so that by turning the screw g the spring f can be lowered, as required. Upon the end of this spring is a platinum piece, j , and another platinum piece, j' , on the gripping-lever d , to form contact to cut out the resistance-coil or second wire upon the solenoid or electro-magnet. The gripping-lever d is suspended at its outer extremity by a spiral spring, k , and an adjusting-screw, k' , which latter passes through the angle-piece B, secured to the top of the frame A. The other end of this gripping-lever is jointed upon two arms, s s' , which are connected to the frame A on each side of the roller a and fit loosely on bush-pieces s'' , let into the frame, through which passes the arbor upon which the roller a revolves. A second solenoid, W, or an electro-magnet is employed to form the arc by separating the upper and lower carbons. It is shown arranged in Fig. 1 on the opposite side of the frame A, with its

spiral spring w , adjusting-screw w' , gripping-lever d' , and arbor much the same as on the feeding side.

B' is a bent arm carrying set-screws t t' , 5 against which the arms s s' rest, allowing the spiral springs k and w to just pull the gripping-levers d d' off the periphery of the roller a . A piece of iron, S , is placed at the bottom of the arc-making solenoid, and is held fast there- 10 in by being screwed into the base-plate. This piece S serves as a magnet to attract and hold down the core N of the solenoid W , which core is attached to the gripping-lever d' . On the arc-making side is an arm or lever, x , bent 15 into the position shown in Fig. 2 and fixed to the axis d^3 of the gripping-lever d' , so that when the iron core N of the solenoid W is drawn into the coil this arm or lever presses against the side of the frame A , and by so doing 20 releases the gripping-lever from the roller a . An upwardly-projecting arm, P , is placed upon the frame of the jockey-roller and is furnished with a pin or stud, p , which is so arranged thereon as to be caught by the feeding-lever d should the carbons be apart, and to 25 act upon and release the jockey-roller and allow the upper carbon to descend by gravity and come into contact with the lower carbon. A short-circuiting arrangement is also placed 30 upon the frame of the jockey-roller, so that when the upper carbon is consumed, or if by accident the carbon should break, contact is made at y upon the insulated stud y' , which is in connection with the — (negative) terminal, 35 and as the + (positive) terminal is in connection with the frame A , short circuit is made and the lamp cut out. If the upper carbon should be consumed until the top of such carbon descends below the roller a , then by the 40 pressure caused by the spring c the upper carbon will be displaced, the jockey-roller will be drawn inward, and the long arm Y will come in contact at y .

y' is a copper wire, making good connection 45 for short circuiting. The wire connecting the short-circuiting stud y' to the — terminal may be of the same resistance as the arc, if required, so that the resistance of the line will remain the same if part of the circuit be turned off.

50 Of course it will be understood that electromagnets will answer the same purpose as the solenoids by using armatures or keepers in place of the iron cores.

My improved construction of lamp may be 55 used either with direct currents or with alternating currents. If alternating currents be used, I then prefer to employ a bundle of iron wires in place of iron tubes or solid iron cores.

The action of the lamp is as follows: When 60 to be lighted, and should the carbons be apart, the current enters at the positive terminal, and, traversing the shunt-coil M , pulls down the core M' until the gripping-lever d comes against the stud p on the arm P , and, displacing the 65 jockey-roller, causes the upper carbon to come into contact with the lower carbon. The current then passing by the thick-wire solenoid W ,

the core of the shunt-coil is drawn back by the spring k , having lost its power by the current passing in the thick wire and through the carbons and arc. The core N is brought down upon the piece of iron S , the arm x displaces the gripping-lever d' after turning the roller a in the proper direction, this being in the direction to raise the upper carbon from the lower one, forming an arc between them. The core N remains down all the time the lamp is alight. As the arc becomes longer by the carbons being consumed, so more current passes by the shunt-coil, passing into it from the frame-work 75 A through S and d to platinum contact j' , at this time touching platinum contact j , up the spiral spring f to the block of metal c , through the wire m into the coil, and through the inner half of the coil out of the inside end of the coil M to the negative terminal, or to the thick-wire-coil end, which is the same thing. This increase of current through this shunt-coil, which is the inner half of coil M , causes the iron M' , suspended to gripping-lever d and spiral spring k , to be drawn into the solenoid-coil M very 80 slowly, which turns the roller a and feeds the upper carbon down until the two platinum contacts be parted. Thus, as the current cannot pass by the gripping-lever d it has consequently to pass by m' from the base-plate, instead of at the frame-work A . Now, it will be seen that the shunt-coil has to conduct the current through the whole of its wire from the base-plate at m' out of its inside end to negative. Thus it has a much greater resistance to 85 pass through, which causes it to exert much less attractive force upon the iron M' , and allows the spiral spring k to pull it up out of the coil M until it again makes contact between the two platinum pieces j' and j , when the outer half or part of the coil M is again short-circuited, and the current passes again by the gripping-lever d through the frame A , as before. Now, if the arc is still of a greater length 90 than required, this extra attractive force again pulls down the iron M' and again breaks at j' and j , and so on, continues the up-and-down motion until the arc is its proper length, when the up-and-down motion ceases until the arc 95 is again longer by the carbons being consumed, which means greater resistance in the arc, and causes more current to flow again by the shunt-coil, which again does its work, as before.

I am aware that the upper electrode in an 100 arc-lamp has been guided and sustained by two rollers at opposite sides of the electrode, one roller being in bearings in a stationary frame and the other roller upon a lever provided with a spring to give the desired pressure upon the 105 electrode, and I am aware that a magnet of low resistance in the lamp-circuit and a magnet of high resistance in a shunt-circuit have been employed for regulating the feed of the upper carbon.

Having fully described my invention, what I 110 desire to claim, and secure by Letters Patent, is—

1. In an electric-arc lamp, the rollers a a' in

- a stationary frame at one side of the electrode, the intermediate roller, a^2 , in a swinging frame at the other side of the electrode, and a spring and adjusting-screw for regulating the pressure 5 of the roller a^2 upon the electrode, in combination with means for turning the roller a , substantially as and for the purposes specified.
2. The swinging frame s , gripping-lever d , and its spring and stop, in combination with 10 the rollers a a' , electrodes, the lever-arm P , and a magnet for actuating said gripping-lever and giving the downward feed to the electrode, substantially as and for the purposes specified.
3. The swinging frame s^2 , gripping-lever d' , 15 and its spring and stop, the arm x , upon said gripping-lever, and a stop for said arm to come against, in combination with the electrodes and a magnet for actuating said gripping-lever, substantially as and for the purposes specified.
4. The swinging frames s s^2 , gripping-levers d d' , their springs and stops, and an arm, x , and stop, in combination with the rollers a a' , electrodes, and means for actuating said gripping-levers, substantially as and for the purposes specified.
- 25 5. The roller a^2 , lever-arm Y , and its spring,
- and rollers a a' , in the stationary frame, in combination with the carbon electrodes, the stationary contact y' , and circuit-connections, as specified, so that when the upper end of the 30 electrode passes below the roller a^2 the lever y is thrown by its spring in contact with y' and closes a circuit between the + and — connections to the lamp, substantially as and for the purposes specified.
6. The combination, with the rollers a a' , gripping-levers d d' , and electrodes, of the magnet W , of low resistance in the main circuit, the magnet M , with a two-part coil of high resistance in a shunt-circuit, and circuit-connections, arranged substantially as and for the purposes specified.
- In testimony whereof I have set my hand, in the presence of two subscribing witnesses, this 8th day of May, 1882.
